Atty.

UNITED STATES PATENT OFFICE

GEORGE STEVENS, OF CHICAGO, ILLINOIS

TONE BAR

Application filed April 25, 1932. Serial No. 607,301.

This invention relates to improvements in tone bars to be used when playing guitars and similar stringed instruments for varying the tone of the music. A particular object of the invention is to provide a bar, preferably of metal, having a particular shape, which adapts it to be held by the operator in a particular manner.

Of the accompanying drawing, Fig. 1 is a perspective elevation of the bar; and Fig. 2 is an end view thereof.

As is well understood, in playing certain stringed instruments when it is desired to give a peculiar tone to the music; for instance, such as is usual with those imitating Hawaiian music; a bar having a rounded surface is used to vary the length or the vibrations of the strings so as to produce the desired notes and also to vary the particular tone of the instrument. It is common, in such a case, to use metal bars, but the material of which the bar is composed is not a necessary feature of my invention.

The bar embodying the features of my invention comprises an elongated bar, such as is shown in Fig. 1, being preferably oblong in general shape, and having a rounded surface 5 which is brought into contact with the string or strings the lengths or the vibrations 25 of which are to be varied by the operator. The bar also comprises means for holding the bar firmly at all times and in a particular manner, so that it can be manipulated accurately, according to the desires of the operator. The holding means comprises a concave portion 6 which is opposite the rounded surface, and in which the operator ordinarily places the first finger of his left hand. The bar comprises also a groove 7 which is adapted to receive the second finger of the operator. In both cases, the grooves have a concave inner side and are substantially of the same shape throughout the length of the bar, so that the fingers at certain times at least 40 can lie extended along substantially the en-

tire bar, thus assisting in the skillful manipulation of the bar. A third groove 8 is preferably formed in the bar, in which the operator places his thumb so as to hold the bar firmly against the fingers in the other 50 grooves. At the same time, the thumb allows the operator to hold the bar more or less firmly and to tilt it one way or the other, as may be desired, for operating the instrument.

In this manner, a bar is formed which has 55 a surface suitable for coming in contact with the strings, and so arranged that it can be skillfully manipulated by the operator so as to vary the length of several strings simultaneously, or one or more strings at a time, as 60 may be desired, and the bar can also be held very firmly against the strings, or loosely thereon, so as to vary as desired the vibrations or the particular tone of the instrument.

I am well aware that various bars for this 65 purpose have been produced, and means have been provided in some cases to assist in holding the bars, but my invention lies in the particular shape of the bar holding means which allows the operator to manipulate the bar 70 more skillfully and artistically than has been the case heretofore.

The material of which the bar is composed may be varied to suit the operator, but I prefer for the purpose a metallic bar composed 75 preferably of brass. Also, the exact dimensions of the bar are not a necessary feature of my invention, but I prefer one of the ordinary length and with the grooves adapted to fit the fingers and thumb of the 80 operator.

I claim as my invention:

1. A tone bar comprising an elongated bar having in general an oblong cross section, but with one edge convex and the opposite 85 edge concave, and with the concave surface extending substantially uniformly across the full length of the bar, the radius of curvature of the concave surface being comparable to the radius of the opposite convex surface. 90

2. A tone bar as claimed in claim 1, and comprising a convex groove extending substantially the full length of the bar on one side between the aforesaid edges.

5 3. A tone bar as claimed in claim 1, and comprising a concave groove extending substantially the full length of the bar on both sides thereof between the aforesaid edges.

In testimony whereof, I hereunto set my
10 hand.

GEORGE STEVENS.
